Fig. 5.

UNITED STATES PATENT OFFICE.

EDWARD F. DUDLEY, OF OAK PARK, ILLINOIS, ASSIGNOR TO MIEHLE PRINTING PRESS AND MANUFACTURING COMPANY, OF CHICAGO, ILLINOIS, A CORPORATION OF ILLINOIS.

PRINTING-PRESS DUCTOR-ROLLER MECHANISM.

Application filed March 3, 1921. Serial No. 449,511.

To all whom it may concern:

Be it known that I, EDWARD F. DUDLEY, a citizen of the United States, residing at Oak Park, in the county of Cook and State 5 of Illinois, have invented certain new and useful Improvements in Printing-Press Ductor-Roller Mechanisms, of which the following is a specification.

Experience has shown that in printing-10 presses it is desirable, even in reciprocatory bed presses, to have the ink fed or transferred substantially continuously and always in the same direction from the ink-fountain or reservoir to the form-inking 15 rollers to secure an even and efficient distribution thereto and to the form.

Conformably to this end, the current invention provides means for the ready accomplishment of this object by supplying 20 the machine with more than one ductor-roller to transfer the ink from the main or ink-fountain distribution-drum to the form vibrator-roller for transmission therefrom to the coacting form-inking rollers.

25 A pair of such oppositely-rotating ductor-rollers may be conveniently employed and they are designed to contact alternately with the vibrator-roller of the form-rollers and they also act part of the time as dis- 30 tributors on the distributing-drum associated with and adjacent to the ink-fountain.

Such an arrangement permits the use of 35 fewer composition-rollers contacting with the form than is usual, a shorter stroke for the bed, and a possible higher speed of action.

In the preferred embodiment of the invention, the form and bed, for example, of the sliding vertical type, are reciprocated by 40 any suitable mechanism such as a crank and connecting-rod, the rate of travel or speed of the bed and its form being variable at least at the beginnings and ends of its strokes because of their reversal of move- 45 ments.

The speed of rotation of the form-inking rollers and their complementary vibrator-roller varies similarly.

On the other hand, the speed of revolution 50 of the distributing-drum of the ink-fountain is constant or uniform and it is, therefore, desirable to so shift the ductor-rollers that they will engage the form vibrator-roller

when the latter after its reversal has attained a surface speed substantially that of 65 the ductor-roller, whereby when they come into contact they will be rotating at the same speed and will not rub on one another.

Similarly each ductor-roller leaves the 60 form vibrator-roller before its surface speed decreases below that of the ink-distributing drum whereby the ductor-roller will engage or come into contact with the latter while both are revolving at practically the same 65 peripheral speed.

For a relatively short period during each 70 reversal of movement of the form and its inking-rollers, both ductor-rollers are co-acting with the distributing-drum to assist in the proper spreading of the ink and to 75 pick up their proper charges of the same for the subsequent transfer to the form-rollers.

The present invention relates to simple 80 mechanical means for accomplishing these and other advantageous aims and purposes, 75 and in order that those skilled in this art may have a full and complete understanding of a construction embodying such invention, in the accompanying drawing a preferred 85 and desirable incorporation of the invention in physical form has been depicted, the same reference characters applying to like parts throughout the several views.

In this drawing:

Figure 1 is a vertical section on line 1—1 85 of Figure 2, the parts being viewed in the direction indicated by the arrows;

Figure 2 is an end elevation of the structure;

Figure 3 is a vertical section on line 3—3 90 of Figure 1;

Figure 4 is a similar section with the ductor-rollers in different positions; and

Fig. 5 is an end view of the printing 95 press, in which illustration the co-operating elements are shown more less diagrammatically.

Turning to the drawing, it will be observed that the machine includes spaced portions 11 and 12 of an appropriate framework 100 accommodating a vertically-reciprocating printing-form bed 13 operated from a crank drive-shaft 101 associated with the sliding form bed by one or more connecting rods 102.

Coacting with the form of such bed are a

pair of composition form-inking rollers 14 and 15 and a companion, intermediate vibrator-roller 16 rotated and reciprocated by the usual and well-known mechanism, where-
5 by the surface speed of the two form-inking rollers conforms always to the variable or fluctuating speed of the reversing bed and form.

In the present instance, this operating
10 mechanism includes a vertical rack 103 mounted on and reciprocable with the form bed 13, its teeth being in mesh with those of a gear 104, which, by intermeshing gears 105, 106, 107, 108 and 109, rotates the form-
15 inking and vibrator rollers in the manner stated.

In this way, it is convenient to drive or slide the bed by such appropriate means and to operate the form-inking and vibrator rollers
20 from the bed or its driving mechanism whereby to secure the required harmony and consonance of action between the coacting elements.

The ink-fountain has not been shown,
25 since it may be of the usual type, but its associated rotary, vibratory distribution-drum 17 is mounted in the frame-work and is revolved at a constant and regular speed.

The means for rotating this drum 17 com-
30 prise an electric-motor 111 operating a horizontal shaft 112 which drives an upright shaft 113 through a worm and worm-wheel connection 114, such vertical shaft in turn rotating the shaft 115 of drum 17 through
35 intermeshing bevel gears 116.

Above such drum 17, and always in contact therewith, is a roller 18 provided partly to effect the distribution of the ink on the drum, but supplied also to obtain a reversal
40 of the direction of rotation of one of the two ductor-rollers 19 and 21.

These two rollers are mounted for rotation in the opposite ends of a pair of supporting arms 22 and 23 apertured at their
45 central parts for the accommodation of and keyed to a shaft 24 oscillatory in aligned bearings 25, 25 at the upper ends of a pair of arms 26, 27 mounted for oscillation on studs 28, 28 supported by and outstanding
50 from the frame elements 11 and 12.

Each arm is supplied with a coil torsion-
55 spring 29 encircling its stud and having its ends secured respectively to the corresponding frame element and to the arm, the two springs tending to rock the arms in a direction to carry shaft 24 toward the distribution-drum 17.

Keyed or otherwise rigidly fastened to
60 shaft 24 is a depending arm 31 equipped at its lower end with a roller 32 coacting with a cam 33 on a suitably-journalled shaft 34 rotated by any approved means, such as a crank 35 and an associated connecting-rod or link 36 driven from any appropriate source
65 of power, not shown.

The operation of the appliance occurs practically as follows:

During the ascent of the bed and its form, the roller 32 then contacting with the outer edge of the cam 33 maintains the arm 31 in 70 such position, as shown in Figure 3, as to hold the ductor-roller 21 in contact with the form vibrator-roller 16 and the complementary ductor-roller 19 in engagement with the intermediate roller 18, whereby the two latter rollers perform the function of distributing the ink on the drum 17.

When, or at about the time, the bed and form begin to reduce speed, during their upward travel, for the reversal of direction of 80 movement, the cam shifts arm 31 to bring the ductor-roller 21 into contact with the distribution-drum 17 while revolving at practically the same surface speed of the latter, the roller 19 still maintaining its contiguity 85 with roller 18, so that during the time of reversal of movement of the bed and form and the form rollers both ductor-rollers are acting as distributors in connection with drum 17 (Figure 2).

As soon as the bed has reversed its direction of travel and is descending at a surface speed substantially that of the roller 19, the cam 33 shifts the rollers into the position shown in Figure 4, in which relation of the parts, the roller 19 contacts with the form vibrator-roller 16, the ductor-roller 21 still performing its function as a distributing-
90 roller.

When the bed and form approach their lower limit of movement and while the speed of roller 19 is practically that of roller 18, it is again moved back to contact with such intermediate roller whereby both ductor-rollers again temporarily act as distributors 105 during the reversal of movement of the form, and as soon as the latter has acquired proper speed during its upper travel the ductor 21 is once more swung into contact with the vibrator-roller 16. Thus the action 110 continues.

It will be seen that, whereas the bed and form and the form-inking rollers and their associated vibrator-roller have a variable speed of movement, and, whereas the distribution-drum has a uniform speed, the positions of the ductor-rollers are altered at the proper moments so that they will have substantially the surface speed of the rollers with which they are about to contact, thus 115 avoiding any undesired or objectionable action of the one on the other.

From an understanding of the construction as detailed above, it will be apparent that the spring-influenced arms 26 and 27 125 tend to cause both ductor-rollers to engage the distribution drum and its intermediate roller, and that the cam by rocking arms 22 and 23 effects the alternate engagement of the ductor-rollers with the vibrator-roller 130

with intervening periods of simultaneous contact with the drum and the intermediate roller. Stated somewhat differently, the ductor-rollers are mounted on a support 5 rockingly carried on a main oscillatory support, the former being cam controlled, the latter spring governed.

It will also be perceived that the two ductor-rollers revolve in opposite directions, 10 and, since they alternately engage the vibrator-roller 16 only when it revolves in opposite directions, the ink is fed or transferred thereto always in the same direction and more or less continuously or uninterruptedly 15 or as nearly so as the variable speeds will permit.

Obviously the invention is not limited to this particular embodiment, being susceptible of a variety of incorporations in physical form, and accordingly many minor 20 mechanical changes may be made in the machine or apparatus illustrated and described without departure from the substance of the invention as defined by the appended claims 25 and without sacrifice of its numerous benefits and advantages.

I claim:

1. In a printing-press inking-mechanism, the combination of form-inking rollers 30 adapted to coat with the same form, a vibrator-roller coacting with said form-inking rollers, means to rotate said form-inking and vibrator-rollers, a distribution-drum, means to rotate said drum, a pair of ductor-rollers, an intermediate-roller adapted 35 to contact with the surfaces of said drum and one of said ductor-rollers, and means to shift the positions of said ductor-rollers to cause them to alternately coat with said vibrator-roller and to cooperate with said drum during their periods of non-engagement with the vibrator-roller, substantially as described.

2. In a printing-press inking-mechanism, 45 the combination of a form-inking roller, a vibrator-roller coacting with said form-inking roller, means to rotate said form-inking and vibrator-rollers at a variable speed, a distribution-drum, means to rotate said drum at a substantially uniform speed, a pair of ductor-rollers, an intermediate-roller adapted 50 to contact with the surfaces of said drum and one of said ductor-rollers, and means to shift the positions of said ductor-rollers to cause them to alternately coat with said vibrator-roller and to cooperate with said drum during their periods of non-engagement with the vibrator-roller, substantially as described.

3. In a printing-press inking-mechanism, 55 the combination of form-inking rollers adapted to coat with the same form, a vibrator-roller coacting with said form-inking rollers, means to rotate said form-inking and vibrator-rollers, a distribution-drum,

means to rotate said drum, a pair of ductor-rollers, an intermediate-roller adapted to contact with the surfaces of said drum and one of said ductor-rollers, and means to shift the positions of said ductor-rollers to cause them to alternately coat with said vibrator-roller and to cooperate simultaneously with said drum during their periods of non-engagement with the vibrator-roller, substantially as described. 75

4. In a printing-press inking-mechanism, the combination of a form-inking roller, a vibrator-roller coacting with said form-inking roller, means to rotate said form-inking and vibrator-rollers at a variable speed, a distribution-drum, means to rotate said drum at a substantially uniform speed, a pair of ductor-rollers, an intermediate-roller adapted 80 to contact with the surfaces of said drum and one of said ductor-rollers, and means to shift the positions of said ductor-rollers to cause them to alternately coat with said vibrator-roller and to cooperate simultaneously with said drum during their periods of non-engagement with the vibrator-roller, substantially as described. 85

5. In a printing-press inking-mechanism, the combination of a form-inking roller, a vibrator-roller coacting with said form-inking roller, means to rotate said form-inking and vibrator-rollers at a variable speed, a distribution-drum, means to rotate said drum at a substantially uniform speed, a pair of ductor-rollers, an intermediate-roller adapted 90 to contact with the surfaces of said drum and one of said ductor-rollers, and means to shift the positions of said ductor-rollers to cause them to alternately coat with said vibrator-roller and to cooperate simultaneously with said drum during their periods of non-engagement with the vibrator-roller, substantially as described. 95

6. In a printing-press inking-mechanism, the combination of an inking roller, means to rotate said roller at a variable speed, a distribution-drum, means to rotate said drum at a substantially uniform speed, a ductor-roller, and means to shift said ductor-roller into and out of contact with said inking roller, such contact occurring when the two rollers are revolving at substantially the same surface speed as said drum or intermediate roller, substantially as described. 100

7. In a printing-press inking-mechanism, 105

the combination of an inking roller, means to rotate said roller at a variable speed, a distribution-drum, means to rotate said drum at a substantially uniform speed, an intermediate-roller adapted to contact with the surface of said drum, a ductor-roller, and means to shift the positions of said ductor-roller to carry it into and out of contact with said inking roller, such contact occurring when the two rollers are rotating at substantially the same surface speed, and into and out of contact with said intermediate-roller, such contact taking place when said two rollers are revolving at substantially the same peripheral speed, substantially as described.

8. In a printing-press inking-mechanism, the combination of an inking roller, means to rotate said roller at a variable speed, a distribution-drum, means to rotate said drum at a substantially uniform speed, an intermediate-roller contacting with the surface of said drum, a pair of ductor-rollers, and means to shift the positions of said ductor-rollers to cause them to contact alternately with said inking roller with intermediate periods in which said ductor-rollers simultaneously cooperate with the intermediate roller and the drum, the contact of said ductor-rollers with said inking roller occurring when both are revolving at substantially the same surface speed, the contact of said ductor-rollers with said drum and said intermediate-roller respectively occurring when the elements about to contact are rotating at practically the same peripheral speed, substantially as described.

9. In a printing-press inking-mechanism, the combination of a form-inking roller, a coacting vibrator-roller, means to rotate said rollers, a distribution-drum, means to revolve said drum, an intermediate-roller adapted to contact with said drum, an oscillatory support, means to oscillate said support, a support rockingly mounted on said oscillatory support, and a pair of ductor-rollers on said rocking support, whereby

said ductor-rollers alternately engage said vibrator-roller with intermediate periods of engagement respectively with said distribution-drum and said intermediate-roller, substantially as described.

10. In a printing-press inking-mechanism, the combination of a form-inking roller, a coacting vibrator-roller, means to rotate said rollers, a distribution-drum, means to revolve said drum, an intermediate-roller adapted to contact with said drum, an oscillatory support, means to oscillate said support, a support rockingly mounted on said oscillatory support, spring means tending to rock said support toward said distribution-drum, and a pair of ductor-rollers on said rocking support, whereby said ductor-rollers alternately engage said vibrator-roller with intermediate periods of simultaneous engagement respectively with said drum and said intermediate-roller, substantially as described.

11. In a printing-press inking-mechanism, the combination of a form-inking roller, a coacting vibrator-roller, means to rotate said rollers at a variable speed, a distribution-drum, means to revolve said drum at a substantially uniform speed, an intermediate-roller adapted to contact with said drum, an oscillatory support, means to oscillate said support, a support rockingly mounted on said oscillatory support, spring means tending to shift said supports toward said drum, a pair of ductor-rollers on said rocking support, whereby said ductor-rollers alternately engage said vibrator-roller with intermediate periods of simultaneous engagement respectively with said drum and said intermediate-roller, the contact of said ductor-rollers with said vibrator-roller, drum, and intermediate-roller occurring when they are rotating at substantially the same surface speed as that of the element with which they are to contact, substantially as described.

EDWARD F. DUDLEY.
